FREQUENCY MODULATION RECEIVER

George L. Usselman, Port Jefferson, N. Y., assignor to Radio Corporation of America, a corporation of Delaware

Application August 21, 1942, Serial No. 455,567

27 Claims. (Cl. 250—8)

The present application relates to timing modulation, such as, phase and frequency modulation and particularly to a new type of timing modulation receiver with automatic frequency control means for keeping the receiver in tune with the incoming wave.

In known timing modulation receivers the deviations in accordance with signals from the mean or base carrier frequency are converted to amplitude variations and the latter are detected. My receiver is different from most timing modulation receivers in that local oscillations of the desired frequency are produced and mixed with the received wave and the direction of phase rotation of the beat note obtained, when the received signal is beat with oscillations from a substantially fixed frequency oscillator, is detected.

In a preferred embodiment the mean or base frequency of the modulated wave when subjected to the demodulation process is the same as the frequency of the oscillations provided by the oscillator. The wave and oscillations are beat one against the other and phase deviations of the beat note (with respect to zero beat) are of a direction and size dependent upon the frequency relation of the wave and oscillations and the extent of difference therebetween respectively. Since in my system detection is of the direction of phase rotation, a limiting action is derived and amplitude variations are eliminated by the inherent operation of the system.

In timing modulation the wave is varied in phase or frequency about a mean or average frequency which can in general be considered the mean between the deviation limits. In space wave signalling a carrier is modulated in frequency alternately at signal frequency between two frequency values and the time during which the wave is deviated in one direction may be greater than the time it is deviated in the other direction so that the average frequency may or may not be the center frequency. It is essential that the receiver be tuned to the center frequency or else the response will be unbalanced.

The receiver of my invention is particularly adapted to use in spaced wave signalling and in all wave length or timing modulation systems.

It is quite important to keep the receiver tuned properly to the incoming signal. This function may be done by hand but that requires constant attention. A much better method is to automatically keep the receiver in tune. Automatic tuning control of amplitude modulation receivers has been quite well worked out.

Ordinary methods of automatic tuning control of frequency modulation receivers have been disclosed previously. These methods usually have the defect that the receiver is tuned on or toward either space or mark, whichever is greater than 50 per cent of the signal time; that is, when known automatic tuning means are used on spaced wave keying they have a tendency to tune to the average frequency rather than the mean frequency.

10: The present invention will keep the receiver tuned in the proper frequency band irrespective of the lengths or weight of space or mark signals.

In describing my invention in detail, reference will be made to the attached drawings wherein two specific embodiments of my invention are shown in Figures 1 and 2. The arrangements of both figures are in general the same and operate in substantially the same manner. In Figure 1 the receiver only is shown. In Figure 2 a second embodiment of the receiver is shown and automatic tuning means is also provided. The tuning means of Figure 2 is to be included with the receiver of Figure 1, if desired.

In Figure 1 wave energy, such as wave energy 25 the frequency of which is shifted between two values by telegraphy signals separated in the frequency spectrum by several thousand cycles is picked up in the aerial 2. The wave may be shifted between a value representing the marking frequency and a second value representing the spacing frequency. The wave is amplified and heterodyned to lower correspondingly spaced frequencies in unit 4. The unit 4 may also include intermediate frequency amplifiers and the energy 30 of intermediate frequency is fed through coupling condenser 5 to the grids 6 and 8 of tubes V1 and V2 respectively by way of phase advancing condenser C cooperating with phasing resistance 9 and phase retarding inductance L cooperating with phasing resistance 10. The condenser C and resistance 9 are such as to advance the phase of the wave in its two positions, while the inductance L and resistance 10 retard the phase of the wave 35 in its two positions. Positive potential for these two electrodes is supplied through resistors 9 and 10 a point on which is connected by blocking and radio-frequency bypass condenser 12 to ground.

Oscillations of constant frequency developed by 50 known appropriate means in unit F are fed through transformer T and parasitic suppression resistances 14 and 16 to the control grids 18 and 20 of tubes V1 and V2. The screen grids 22 and 24 are connected to a source of direct current 55 which is shunted by bypass condenser 26. The

negative potential source (not shown) for control grids 18 and 20 is shunted by bypass condenser 28.

The anodes 30 and 32 are connected by radio-frequency filter circuits 34 and 36 and impedance couplings 44 and 46 to the control grids 52 and 54 of the tubes 56 and 58. The anode 60 of tube 56 is connected to the source 62 through resistance 64 and relay winding 66. A similar connection runs from the anode 70 of tube 58 through resistance 74 and relay winding 76. The cathodes of tubes 56 and 58 are connected together and to a positive point on source 62, this section of which is shunted by bypass condenser 51. The windings 66 and 76 cooperate with armature K and two contacts to complete two circuits having a common leg. For example, these circuits may be connected to an indicator or recorder, or may control or key a tone generator connected to a recorder or indicator of other type.

The anode 60 of tube 56 is connected to the grid 54 of tube 58 through resistance 61. A similar connection runs through resistance 71 between the anode 70 of tube 58 and grid 52 of tube 56. The tubes 56 and 58 with their cross-connected anodes and grids form a tripping circuit wherein current is tripped from one tube to the other by the excitation voltage. In the absence of applied voltage on the grids, the circuits and tubes are in a state of unbalance and unequal currents which may be large and small (or zero) flow in their anode circuits.

If the grid of one tube, say tube 56, is made less negative or more positive this tube draws current and the current flowing in its anode circuit produces in the anode resistance 64 a negative potential which is transferred to the grid 54 of the other tube 58 to make it draw less current. This switches the current to the first tube 56 and from the second tube 58. This condition remains and pulls the contact K to one side until an applied potential on the grid of the other tube 58 starts it to draw current and produce a potential in resistance 74 and this acts through the cross connections to switch the current to the other tube 58 and from the first tube 56. Tube arrangements of this type are known in the art and have been disclosed more in detail in J. L. Finch U. S. Patent No. 1,844,950.

In Figure 1 the inductances L1 and L2 with the condensers C1 and C2 are for the purpose of preventing radio-frequency current from reaching the tripping circuit. Resistors R1 and R2 are for damping out parasitics. However, they may be omitted where screen grid tubes are used.

The arrangement of Figure 2 is similar in many respects to the arrangement of Figure 1 but differs therefrom in other respects. The modulated wave of reduced frequency is fed in phase displaced relation to the control grids 18' and 20' and the point on resistors 9 and 10 is supplied by a negative potential. The source F is coupled to the grids 6' and 8' by a coupling condenser 7 and a radio-frequency impedance L1.

The anodes 30 and 32 are connected by resistors 31 and 33 respectively to the primaries of transformers T1 and T2 and through these primaries to a source of anode potential. Anodes 30 and 32 are grounded for radio frequencies by condensers 35 and 37 connecting the anodes 30 and 32 respectively to ground. Condensers 39 and 41 serve to balance the tubes and transformer inputs with respect to ground. They are

also part of the radio-frequency filter. The secondary windings of transformer T1 and T2 are coupled by resistances 43 and 45 to the grids of the electron systems of the tripping circuit. In both modifications the tube systems of the tripping circuit may be included in a single envelope or in separate envelopes.

The receiver of Figure 2 is essentially the same as the receiver of Figure 1 and differs therefrom mainly in the manner of coupling the tripping circuit including tubes 56 and 58 to the output of the phase detectors V1 and V2. In Figure 1 capacity coupling is used, while in Figure 2 transformer coupling is used.

In order to tune the receivers automatically a tuning means as shown in Figure 2 may be used. This tuning means includes an amplifier tube V5 having its control grid 90 coupled to the output of the phase detector at, say 31, and its anode 94 coupled to a load resistance 98 points on which are coupled by a high pass filter Z to a rectifier V6, the output of which is in series with a relay (#2 relay) armature and one or the other of the two windings of a relay (relay #3) the armature of which cooperates with two contacts in the field winding circuits of a reversible field motor M, the shaft of which drives a tuning reactance Y in the oscillation generator circuit of the receiver 4. The #2 relay windings are connected to the output of the tripping circuit including tubes 56 and 58 say in shunt to the windings 66 and 76 of the output relay identified here as relay #1.

My invention, it is believed, will be understood by those skilled in the art from the above description. However, a statement of the operation will now be given. In doing so, reference will first be made to Figure 2. Assume that the frequency modulated carrier wave received on antenna 2 is shifted through about + and -2500 cycles, or a total of 5000 cycles. This signal carrier wave is amplified and heterodyned to a lower frequency, say about 1,000,000 cycles average or mean frequency, which may again be amplified before it leaves the unit 4. The 1,000,000 cycle wave is correspondingly shifted plus and minus 2500 cycles the two frequencies representing mark and space conditions. The frequency modulated or shifted intermediate frequency wave (1,000,000) cycles is delivered to the control grids 18' and 20' of detector tubes V1 and V2 through phase shifter elements C9 and L10 respectively. The phase shifter condenser C with resistor 9 advances the phase of the excitation, that is, either mark or space frequency, reaching the control grid of tube V1, while the phase shifter inductance L with resistor 10 retards the phase of the excitation, that is, either mark or space frequency, reaching the grid of tube V2. Consequently, there is a phase difference between the excitation potentials on the control grids of the two detector tubes V1 and V2. This phase difference is preferably in the order of 45 to 90°.

The frequency at the output of source F is substantially constant and preferably is the same frequency as the carrier or center frequency delivered by unit 4. The output of source F is delivered in parallel to the third grids 6' and 8' of detector tubes V1 and V2 through resistors 14 and 16. The resistors 14 and 16 are used to prevent parasitics.

Now the keyed oscillating potentials from the units 4 and constant frequency potentials from 75 F, both being impressed on the grids of detector

tubes **V1** and **V2**, cause a beat frequency to appear in the outputs of these detectors tubes. This double detector including tubes **V1** and **V2** not only again reduces the frequency but also detects the direction of phase rotation of the beat note which now represents the signal. This beat frequency is of the same frequency, say 2500 cycles, in each detector tube but there is a phase difference determined by the values of the phase shift elements **C9** and **L10**. If, during the modulating cycle, the frequency of the output of unit **4** is higher than that of unit **F**, then the phase of the beat oscillations of tube **V1** will lead that of tube **V2**. Also, if the frequency of the output of unit **4** is lower than that of unit **F**, then the phase of the beat oscillations of tube **V2** will lead that of tube **V1**.

With respect to each detector its beat note is about 2500 cycles for mark and for space but shifts from one adjusted phase position through zero phase and frequency to a new opposed phase position each time the carrier is shifted from marking frequency to spacing frequency and vice versa. Thus, for mark we have a 2500 cycle beat note of one phase rotation and for space a 2500 cycle beat note of opposite phase rotation.

These beats which are of zero frequency when the output of **F** and the mean frequency of **4** are the same are fed to transformers **T1** and **T2** and thence to the tripping tubes **56** and **58**.

The tripping circuit including the tubes **56** and **58** will be actuated by the beat oscillations delivered from detector tubes **V1** and **V2** through transformers **T1** and **T2** respectively. In the tripping circuit only the side **E** or **D** carries blocks of current at one time. For example, if the frequency from unit **4** is higher than that from unit **F**, detector tube **V1**, wherein the beat note of leading phase appears, will trip the **E** side of the tripping circuit. This will then carry a block of direct current during a time (beat frequency cycle) equivalent to, say 60°. Then detector tube **V2** trips tube **58** so that the **D** side of the tripping circuit carries a block of direct current equivalent to 300°. Consequently, the relay **K** will be pulled, say to the lower contact. Now, by similar sequence, if the frequency output from unit **4** is lower than that from unit **F**, detector tube **V2**, wherein the beat note of leading phase appears, will trip the side **D** of the tripping circuit so that this tube takes the current for the shortest time and then the upper side of the tripping circuit will carry the long blocks of current, and, consequently, it will carry the more average direct current and relay **K** will be pulled upward.

Stated in another way, suppose that the phase shifters **C9** and **L10** were such as to produce 180° or phase opposed relation between the beat notes fed from tubes **V1** and **V2** to the tripping circuit. Then the two sides of the tripping tubes each draws current about one half the beat note cycle and their average currents are equal, and the armature of **K** will remain in the neutral position. This is because one side is excited by the leading beat note and current is tripped to that one side for half a cycle at which time the beat note of lagging phase excites the other side of the tube and current is then tripped to the other side for half a cycle of the beat note. However, here the phase displacement is, say 60°, so that the beat note of leading phase trips the current to one side and it flows in that side during 60/360 of a cycle of the beat note frequency at

which time the note of lagging phase acts on the other side to trip the current to the other side where it stays for 300/360 of a cycle of the beat note so that the average current through the said other side is the greater. This has been fully explained in my Patents No. 2,018,820 and No. 2,044,749.

Now it can be seen that as the signal frequency is modulated up and down, as it would be in the case of spacing wave keying, the phase relations of the two beat notes from the detector tubes **V1** and **V2** will cause the keying relay **K** to operate in accordance with the keying of the transmitter.

In the embodiment shown the armature **K** cooperates with two contacts designated **R** and **L** to key the output of a tone generator to convey the intelligence over wire lines to a traffic office. The said keyed tone may be used for other purposes, such as, for example, to key a transmitter to thereby relay the intelligence to a third point.

Now it may be seen in this assumed case, if the receiver or transmitter frequency drifts over 2500 cycles, phase reversals in the second detector tubes **V1** and **V2** will not take place and the receiver will not function. If 5000 cycles plus and minus frequency deviation is assumed, then a frequency drift of 5000 cycles can take place before the receiver fails to function, etc. This frequency drift is compensated for by the present invention which automatically keeps the receiver tuned in the proper frequency band.

The automatic frequency control means will now be described:

Excitation is obtained for the grid **90** of amplifier tube **V5** from the output of one of the second detector tubes, **V1**, in this case. The amplified detected signal frequency energy from stage **V5** is fed into high pass filter **Z**. The output of filter **Z** is fed to rectifier **V6** by way of transformer **T3**. We will assume that filter **Z** will pass through energy whose frequency is above 2500 cycles. Consequently, if the receiver drifts in either direction so that the mark or space detector output frequency is over 2500 cycles, the filter **Z** will pass this frequency and it will be rectified in rectifier **V6**. This rectified current is delivered to the tongue **K1** of relay **#2**. The winding of relay **#2** is connected in parallel with the winding of relay **#1**, which is in the output circuit of tubes **V3**, **V4** as shown. Depending upon the phase rotation of the signal, the relay **#2** will be operated to left **L** or right **R**. Rectified current is at this time flowing in rectifier **V6** and that half of the winding of relay **#3** put in circuit by movement of armature **K1**. This causes similar operation of the armature **K2** of relay **#3**, and the motor **M** is operated counter-clockwise or clockwise. Motor **M** turns a condenser or variable inductance in the frequency controlled heterodyned oscillator which varies the oscillator frequency. Consequently, the average intermediate frequency is changed.

Now, if the direction of this sequence of operation is correctly made, the tuning control apparatus will automatically bring the receiver back in tune for proper operation. In other words, the high pass filter **Z** determines when and how much the receiver should be retuned and the relay **#2** through the second detector and tubes **56** and **58** determines the sense or direction in which this retuning must be made. It may be seen now that the weight or relative lengths of the mark and space elements of the signal have nothing to do with the auto-

matic tuning of the receiver. If either the mark or the space part of the signal begins to edge out of the operating band the tuning of the receiver is automatically corrected to insure proper operation by bringing the receiver back into the operating band.

In the condition where the receiver is so much out of tune that there are no phase reversals in the second detector output (that is, tubes V1, V2 and 56 and 58), the relays #1 and #2 will be pulled constantly to one side making contact continuously on one side of the relay. Then since filter Z and transformer T3 and rectifier V6 are supplying current to the tongue of relay #2, the automatic tuning process will be continuous until the receiver is brought back in tune.

In the condition where the receiver is only partly or slightly out of tune, or, in other words, where the edges of the marks or spaces are beyond the frequency band limits, there will still be phase reversals and the relays #1 and #2 will vibrate, moving the tongue alternately between the two contacts. However, the filter Z and transformer T3 and rectifier V6 will only rectify and supply current when the relay tongue is touching one contact. This will be the contact which causes the control system to correct the receiver frequency. In other words, the rectified current from T3—V6 in this case is synchronized with the motion of the tongue of relay #2 so as to correct the out-of-tune condition of the receiver.

Relay #3 is of a type in which the tongue does not touch either contact when no current is flowing through its coils. Parts of the circuit not explained are assumed to be easily understood because the symbols used are standard.

This invention can be used for automatic tuning control on the conventional type frequency modulation receiver by employing a source as at F and tubes V1, V2, and 56, 58, in addition to the automatic tuning apparatus shown in this invention. By using special transformers for T1—T2, tuning correction can be obtained over a wide range.

Many modifications may be made in this receiver tuning control and still be within the scope of this invention. For instance, any number of amplifiers may be used in place of tube V5. Any suitable type of filter may be used for unit Z. Any suitable type of rectifier may be used in place of T3—V6, such as, oxide rectifiers. The foregoing stages may also be of the push-pull type.

The keying relay 66, 76 and K may be replaced with any desirable response equipment like a transformer and a speaker unit or a reversing direct current motor, etc. The output leads of relay #1 may be in the circuit of recording apparatus.

The tripping circuit may also include inhibiting means, such as those described in my Patents Nos. 2,018,820 and 2,044,749, to stop operation of the tripping circuit when no signal is being received.

Receiver circuits of this type may be used for holding facsimile and television receivers in synchronism with the carrier or average frequency of the transmitter.

This receiver may be used to operate a motor to steer a boat or airplane, in which case one frequency would turn the rudder in one direction and the other frequency would turn the rudder in the opposite direction.

The phase rotation detector and the tripping circuits in this receiver act as both signal ampli-

tude limiter and frequency modulation detector. It is at the same time an amplitude and a frequency modulation limiter because it operates on the change of phase rotation of the detected signal and its operation is substantially independent of changes in amplitude and frequency deviation of the signal.

The oscillators in the heterodyne unit 4 and the comparison unit F in Figure 1 may be very constant frequency crystal oscillators and it would also be desirable for the average or carrier frequency of the transmitter to be very constant. Otherwise, the oscillators in units 4 and F could be provided with vernier hand adjustments, or with automatic tuning means as shown in Figure 2.

The receiver of Figure 1 operates substantially in the same manner in which the receiver of Figure 2 operates, excepting the automatic tuning.

I claim:

1. The method of simultaneously limiting the amplitude and demodulating wave energy the frequency of which is shifted from one frequency value for one signalling condition to another frequency value for another signalling condition which includes the steps of producing oscillations of substantially fixed frequency intermediate the frequencies between which said wave energy is shifted, beating said oscillations and wave energy one against the other to produce a beat note of substantially fixed frequency the phase or frequency rotation of which is in one direction or the other, depending on the relative positions of said wave energy and said oscillations in the frequency spectrum, and detecting the phase changes only of said beat note.

2. The method of demodulating wave energy the frequency of which is shifted from one frequency value for one signalling condition to another frequency value for another signalling condition which includes the steps of producing oscillations of substantially fixed frequency intermediate the frequencies between which said wave energy is shifted during the said signalling conditions, beating said oscillations and wave energy to produce a beat note the phase or frequency rotation of which is in one direction or the other, depending on the relative positions of said wave energy and said oscillations in the frequency spectrum, and producing indications of the direction of rotation of said beat note.

3. The method of demodulating wave energy the frequency of which is shifted from one frequency to another frequency in a manner to represent signals, which includes the steps of producing oscillations of substantially fixed frequency substantially equal to the mean value of the frequencies between which said wave energy is shifted, producing a phase displacement of less than 180° between two portions of said shifted wave energy, beating both of the wave energy portions with said oscillations to alternately derive two beat notes of like frequency, and of phases which depend on the relative positions of said wave energy and said produced oscillations, and producing currents characteristic of the phase relation of said beat notes.

4. The method of demodulating wave energy, the frequency of which is shifted from one frequency to another frequency in a manner to represent signals, which includes the steps of producing oscillations of substantially fixed frequency equal to the mean of the frequencies between which said wave energy is shifted, advancing

the phase of a portion of said shifted wave energy retarding the phase of another portion of said shifted wave energy, beating the wave energies of advanced phase and of retarded phase with said oscillations to alternately derive two beat notes, and producing currents characteristic of the phase relation of said beat notes.

5. In a system for demodulating a signal carrying wave which alternates between a spacing frequency and a marking frequency separated by a band of frequencies, a converter tube and circuit, a source of oscillations of a frequency intermediate the marking and spacing frequencies, a coupling between said source of oscillations and said converter tube, a circuit for impressing said signal carrying wave on said converter tube whereby a beat note is produced by said converter tube the phase of which alternates in direction of rotation depending on the frequency relation of the oscillations and the wave, and a phase detector coupled to said converter circuit.

6. The method of automatically tuning a receiver, responsive to signals comprising a carrier shifted in frequency from a first frequency to a second frequency, to a mean frequency intermediate said first and second frequencies irrespective of inequality in the division of time during which said carrier is at said first and second frequencies which includes the following steps, generating oscillations of substantially fixed frequency substantially equal to said mean frequency, beating said shifted carrier with said oscillations to produce a beat note the frequency of which depends on the frequency relation of said first and second frequencies to said mean frequency and the direction of phase rotation of which reverses as said carrier is shifted, producing current characteristic of the direction of phase rotation of said beat note and controlling the mean frequency of said carrier in accordance with said produced currents when the beat note is of a frequency greater than a selected value.

7. The method of automatically tuning a heterodyne receiver, responsive to signals comprising a carrier shifted in frequency from a first frequency to a second frequency, to a mean frequency intermediate said first and second frequencies irrespective of inequality in the division of time during which said carrier is at said first and second frequencies which includes the following steps, generating oscillations of substantially fixed frequency substantially equal to said mean frequency, beating said shifted carrier with said oscillations to produce a beat note the frequency of which depends on the frequency relation of said first and second frequencies to said mean frequency and the direction of phase rotation of which reverses as said carrier is shifted, producing current characteristic of the direction of phase rotation of said beat note, controlling the mean frequency of said carrier in accordance with said currents, and inhibiting said controlling action when the beat note is of a frequency less than a selected value.

8. The method of receiving signals comprising a carrier shifted in frequency from a first frequency to a second frequency substantially equally spaced with respect to a mean frequency intermediate said first and second frequencies and preventing inequality in the division of time during which said carrier is at said first and second frequencies from preventing such reception which includes the following steps, generating oscillations of substantially fixed frequency

substantially equal to said mean frequency, beating said shifted carrier with said oscillations to produce a beat note the frequency of which depends on the frequency relation of said first and second frequencies to said mean frequency and the phase rotation of which reverses as said carrier is shifted, detecting the phase of said beat note to derive the signals, producing direct current the direction of flow of which is characteristic of the direction of phase rotation of said beat note, and controlling the mean frequency of said carrier in accordance with said produced current when the beat note is of a frequency greater than a selected value.

15. 9. In a receiver of carrier current keyed from a first frequency to a second frequency in accordance with signals, tunable means for heterodyning said keyed carrier current to a lower frequency to produce current of lower frequencies correspondingly keyed from a first to a second frequency, a source of oscillations of a frequency intermediate said lower first and second frequencies, means for beating oscillations from said source with said lower frequency currents from said heterodyne to produce a beat note the direction of phase rotation of which depends on the position of said current of lower frequency as keyed relative to oscillations from said source of oscillations, means for producing a current characteristic of the direction of phase rotation of the beat note for reproducing said signals, other means for producing a direct current when the frequency of said beat note exceeds a predetermined value, an automatic tuning control device coupled with said tunable means, an operating circuit including circuit closing contacts for said device, a connection between said other means and at least one of said contacts, and a relay having an armature associated with at least one of said contacts for completing said operating circuit and supplying thereto the direct current produced by said other means when said armature is actuated, said relay having two armature actuating windings coupled to said first named current producing means.

10. 50. In a receiver of carrier current keyed from a first frequency to a second frequency in accordance with signals, a tunable oscillator for heterodyning said keyed carrier to a lower frequency to produce current of lower frequency correspondingly keyed from a first to a second frequency, a source of oscillations of a frequency intermediate said lower first and second frequencies, phase detecting discharge systems for beating oscillations from said source with said lower frequency currents from said heterodyne to produce a beat note the direction of phase rotation of which depends on the keyed position of said current of lower frequency relative to oscillations from said source, a phase rotation detector for producing a current the direction of flow of which is characteristic of the direction of phase rotation of the beat note, a high pass filter and a rectifier for producing a direct current when the frequency of said beat note exceeds a predetermined value, a variable reactance in said tunable oscillator, a control means for said variable reactance, said control means having an actuating circuit including contacts which when closed connect said actuating circuit to said rectifier, and a contact closing relay having a winding coupled to said phase rotation detector and having an armature associated with said contacts.

70. 11. In a system for receiving a carrier keyed in accordance with signals from a first frequency

to a second frequency, a heterodyning system including a tunable source of oscillations and having an input and an output, the frequency of the energy of the output being determined by the tune of the oscillator, means for impressing said wave energy on the input of said heterodyne system, means for selecting side band currents correspondingly keyed between first and second frequencies from the heterodyne system, a source of oscillations of substantially constant frequency of a value intermediate said first and second frequencies of said side band currents, a mixer tube coupled to said source and to the output of said heterodyne system, said mixer tube having an output wherein a beat note is produced of a frequency dependent on the relative frequencies of said side band currents and oscillations from said source and of a phase rotation which reverses as said side band current is keyed, a tripping circuit coupled to the output of said mixer, a utilizing circuit coupled to said tripping circuit, a motor connected with a tuning element in said heterodyne oscillator said motor having windings the direction of flow of current through which determines the direction of rotation of the motor, a high pass filter coupled to the output of said mixer tube, a relay having windings coupled to the output of said tripping circuit, said relay having an armature for controlling the position of an additional contact cooperating with other contacts, a rectifier coupling the output of said high pass filter to the said additional contact controlled by the armature of said last named relay and a source of potential adapted to be connected to a winding of said motor to supply direct current thereto when the armature of said relay moves said additional contact against one of said other contacts.

12. In a receiver of carrier energy, the frequency of which is keyed from a first frequency to a second frequency in accordance with signals, a tunable oscillator for heterodyning said carrier to a lower frequency, a pair of electron discharge devices having input and output electrodes, a source of oscillations of a substantially constant frequency intermediate said first and second frequencies coupled to input electrodes of said pair of devices, a phase splitting circuit coupling said heterodyne to input electrodes of said pair of devices, a tripping circuit comprising a second pair of electron discharge tubes having input and output electrodes with cross-coupling between the input and output electrodes of the tubes, means coupling the input electrodes of said last pair of tubes to the output electrodes of said first pair of devices, a relay comprising an armature and a pair of windings coupled to the output electrodes of said second pair of tubes, a first contact the position of which is controlled by said armature, an amplifier having an input and an output with the input coupled to the output of one of said first named pair of devices, a rectifier coupled to said first contact, a high pass filter having an input coupled to the output of said amplifier and having an output coupled to said rectifier, a second relay having an armature and having a pair of windings associated therewith and connected to other contacts associated with the said first contact the position of which is controlled by the armature of said first relay, an additional contact the position of which is controlled by the armature of said second relay, a reversible motor connected to a tuning reactance in said heterodyne oscillator and field windings for said motor connected

with still other contacts associated with the additional contact the position of which is controlled by the armature of said second named relay.

- 5 13. In means for effectively limiting the amplitude of and demodulating wave energy the frequency of which is shifted from one frequency for one signalling condition to another frequency for another signalling condition, a source of oscillations of a frequency intermediate said one and another frequencies, a converter circuit excited by said oscillations and said wave energy to produce a beat note the phase of which reverses when the wave energy is shifted from said one to said other frequency and vice versa and a phase rotation detector coupled to said converter circuit.
- 10 14. In a system for demodulating wave energy the frequency of which is keyed between mark and space frequencies in combination, circuits for beating said wave energy with oscillations of a frequency intermediate said mark and space frequencies to produce a beat note the direction of rotation of which reverses as said wave energy is keyed from mark to space frequencies and vice versa and a phase rotation detector coupled to said circuits.
- 15 15. In a signal modulated carrier wave receiver, a circuit excited by the modulated carrier wave for producing current the phase of which rotates and the direction of rotation of which represents the carrier wave modulations and a combined phase rotation detector and signal limiter coupled to said circuit.
- 20 16. In a signal modulated carrier wave demodulating system, a circuit excited by the carrier wave for producing current the phase of which rotates and the direction of rotation of which represents modulation of the wave relative to its unmodulated state, a phase rotation detector coupled to said circuit, and a modulated wave frequency stabilizing circuit controlled by the output of said detector.
- 25 17. A system as recited in claim 14 wherein said phase rotation detector also effects limitation of the amplitude of the wave.
- 30 18. In a system for demodulating wave energy the frequency of which shifts between a first value and a second value in accordance with signals, a circuit for producing current the direction of phase rotation of which represents the wave shifts from said first to second value and vice versa, a detector of the direction of phase rotation of said produced current coupled to said circuit, a circuit coupled to said detector and controlled by its output for producing direct current the direction of flow of which reverses with changes in the direction of phase rotation of said first mentioned produced current and a signal relay coupled to said last named circuit.
- 35 19. A system as recited in claim 18 wherein said phase rotation detector also effects amplitude limiting of the wave and wherein a wave frequency stabilizing circuit is coupled to said last named circuit.
- 40 20. In a system for receiving a carrier keyed in accordance with signals from a first frequency to a second frequency, a heterodyning system including a tunable source of oscillations and having an input and an output, the frequency of the energy of the output being determined by the tune of the oscillator, means for impressing said wave energy on the input of said heterodyne system, a source of oscillations of substantially constant frequency of a value intermediate said first

and second frequencies, a mixer tube coupled to said source and to the output of said heterodyne system, said mixer tube having an output wherein a beat note is produced of a frequency dependent on the relative frequencies of said carrier and oscillations from said source and of a phase rotation which reverses as said carrier is keyed, a tripping circuit coupled to the output of said mixer, a utilizing circuit coupled to said tripping circuit, a motor connected with a tuning element in said heterodyne oscillator said motor having windings the direction of flow of current through which determines the direction of rotation of the motor, a high pass filter coupled to the output of said mixer tube, a relay having windings coupled to the output of said tripping circuit, said relay having an armature for controlling the position of an additional contact cooperating with other contacts, a rectifier coupling the output of said high pass filter to the said additional contact controlled by the armature of said last named relay and a source of potential adapted to be connected to a winding of said motor to supply direct current thereto when the armature of said relay moves said additional contact against one of said other contacts.

21. In a receiver of carrier currents keyed from a first frequency through a mean frequency to a second frequency in accordance with signals, a source of oscillations of a frequency substantially equal to said mean frequency, a pair of electron discharge tubes having input and output electrodes, a coupling between said source of oscillations and the input electrodes of said tubes, a coupling to the input electrodes of said tubes for impressing said carrier currents thereon, phase shifting means in one of said couplings for producing a phase displacement between the excitation currents applied by the said one coupling to the input electrodes of said tubes, the arrangement being such as to produce beat notes which are of substantially constant frequency the phase rotation of which reverse as the said carrier currents are shifted through said mean frequency between said first and second frequencies, and recording means coupled with the output electrodes of said tubes.

22. In a receiver of carrier currents keyed from a first frequency through a mean frequency to a second frequency in accordance with signals, a source of oscillations of a frequency substantially equal to said mean frequency, a pair of electron discharge devices having input and output electrodes, a coupling between said source of oscillations and the input electrodes of said devices, a coupling to the input electrodes of said devices for impressing said carrier currents thereon, phase shifting means in one of said couplings for producing a phase displacement between the excitation applied by the said one coupling to the input electrodes of said devices, the arrangement being such as to produce beat notes which are of substantially constant frequency the phase rotation of which reverse as the said carrier currents are shifted through said mean frequency between said first and second frequencies, an electron discharge tube system, responsive to phase changes of said beat notes, having output electrodes and having input electrodes coupled to the output electrodes of said devices, and recording means coupled to the output electrodes of said tube system.

23. In a receiver of carrier currents keyed from a first frequency through a mean frequency to

a second frequency in accordance with signals, a source of oscillations of a frequency substantially equal to said mean frequency, a pair of electron discharge tubes having input and output electrodes, a coupling between said source of oscillations and the input electrodes of said tubes, a coupling to the input electrodes of said tubes for impressing said carrier currents thereon, phase shifting means in one of said couplings for producing a phase displacement between the excitation currents applied by the said one coupling to the input electrodes of said tubes, the arrangement being such as to produce beat notes which are of substantially constant frequency the phase rotation of which reverse as the said carrier currents are shifted through said mean frequency between said first and second frequencies, a tube system, responsive to beat note phase changes, having output electrodes and having input electrodes coupled to said pair of tubes, apparatus for stabilizing the mean frequency of said keyed currents, and a control circuit conditioned by energy derived from the output electrodes of said tube system for putting said stabilizing apparatus in operation when the beat note frequency exceeds a selected value.

24. In a receiver of carrier current keyed from a first frequency through a mean frequency to a second frequency in accordance with signals, a source of local oscillations of a frequency intermediate said first and second frequencies, means for beating oscillations from said source with said keyed currents to produce a beat note the direction of phase rotation of which depends on the frequency of said current relative to the frequency of said oscillations, means for producing current characteristic of the direction of rotation of the beat note for reproducing said signals, means for producing a control current, when the mean frequency of said carrier current shifts so that the frequency of said beat note exceeds a predetermined value, of a character determined by the direction of rotation of the beat note, and means actuated by said last named control current for preventing said shifts in the mean frequency of said keyed current.

25. In a receiver of carrier current keyed from a first frequency through a mean frequency to a second frequency in accordance with signals, a source of local oscillations of a frequency intermediate said first and second frequencies, means for beating oscillations from said source with said keyed currents to produce a beat note the direction of phase rotation of which depends on the frequency of said current relative to the frequency of the oscillations, means for producing a current characteristic of the direction of rotation of the beat note for reproducing said signals, means for producing a direct current, when the mean frequency of said carrier current shifts so that the frequency of said beat note exceeds a predetermined value, the polarity of the direct current being determined by the direction of rotation of the beat note, and means actuated by said last named direct current for preventing said shifts in the mean frequency of said keyed current.

26. In a receiver of carrier current keyed from a first frequency through a mean frequency to a second frequency in accordance with signals, a source of local oscillation of a frequency intermediate said first and second frequencies, means for beating oscillations from said source with said keyed currents to produce a beat note the direction of phase rotation of which depends on the

keyed position of said current, tube means for detecting the direction of rotation of said beat note, signal recording means coupled to said detector, a rectifier for producing a direct current when the mean frequency of said carrier current shifts so that the frequency of said beat note exceeds a predetermined value, apparatus for stabilizing the mean frequency of said keyed current, said apparatus including an actuating circuit with contacts which when closed includes the output of said rectifier in said circuit, and a relay having windings coupled to said detector and having an armature associated with said contacts.

27. In a receiver of carrier currents keyed from a first frequency through a mean frequency to a second frequency in accordance with signals, a source of oscillations of a frequency substan-

tially equal to said mean frequency, a phase rotation detector excited by keyed currents and oscillations from said source for producing a beat note the frequency of which is substantially constant when said mean frequency is constant and the direction of rotation of which depends upon the frequency of said keyed current with respect to the frequency of said oscillations, means for detecting the direction of rotation of said beat note and recording the same, means for producing a direct current when the said mean frequency shifts and the frequency of said beat note exceeds a predetermined value, the polarity of said direct current corresponding to the direction of rotation of said beat note, and means controlled by said direct current for returning said mean frequency to a predetermined value.

GEORGE L. USSELMAN.
